MANUALLY OPERABLE CIGARETTE
ROLLING MACHINE

Paul Gay, Trion, Ga.

Application July 23, 1931. Serial No. 552,720

1 Claim. (Cl. 131—42)

This invention relates to cigarette rolling machines of the manually operable type, and has for one of its objects to provide a novel, simple and inexpensive machine of this character which 5 shall have the several parts thereof made of such size and so compactly arranged as to adapt it to be conveniently carried in the pocket, which shall be adapted to permit cigarettes to be rolled from any type of tobacco, and which shall be capable 10 of being easily operated and adapted when operated to make a perfectly rolled cigarette.

To attain the foregoing and other objects, the nature of which will appear as the description proceeds, the invention comprehends the provision 15 of a cigarette rolling machine which shall embody a table provided with a recess, an apron overlying the table and terminally secured thereto at opposite sides of the recess, the apron having a portion thereof positioned in the recess to 20 provide a loop for the reception of the tobacco from which the cigarette is to be made and the apron being adapted to support beyond the loop the paper from which the wrapper of the cigarette is to be made, a roller positioned between 25 the table and apron and normally located at one side of the recess and loop, and a carrier for the roller slidably mounted on the table to move the roller across and beyond the recess and loop so as to close the open upper side of the loop 30 and thereafter actuate the apron to carry the loop out of the recess to place the tobacco in the paper, to roll the paper about the tobacco, and to discharge the rolled cigarette from the 35 apron.

35 The invention is hereinafter more fully described and claimed, and illustrated in the accompanying drawing, wherein:—

Figure 1 is a top plan view of a cigarette rolling machine constructed in accordance with my 40 invention.

Figure 2 is a longitudinal sectional view taken on the vertical plane indicated by the line 2—2 of Figure 1.

Figure 3 is a transverse sectional view taken 45 on the vertical plane indicated by the line 3—3 of Figure 1, and

Figure 4 is a perspective view of the roller carrier of the cigarette rolling machine.

The cigarette roller comprises a base 1 which 50 is of elongated rectangular formation in plan and which is made from sheet metal. The base 1 is offset downwardly near one end thereof, as at 2, and this offset portion provides a substantially semi-cylindrical recess 3 which extends 55 transversely of the base and which is closed at

its ends and fully open at its upper side. The base 1 is provided at that end thereof nearer the recess 3 with an upstanding flange 4 which extends transversely of the base and which is formed integrally therewith. Bearing brackets 60 are formed integrally with and extend inwardly from the ends of the flange 4. That end portion of the base 1 remote from the recess 3 is offset downwardly, and this offset portion 6 also extends transversely of the base and comprises 65 a bottom member 6a and end members 6b. The end members 6b connect the bottom member 6a to the base 1, and also constitute bearing brackets.

The side or longitudinal edges of the base 1 are turned upwardly and inwardly to provide guide 70 grooves 7 which extend from one end of the base to the other end thereof.

A pin 8 is located above and extends transversely of that end of the base nearer the recess 3, and a pin 9 is located below and extends transversely 75 of that end of the base remote from the recess, the former being carried by the bearing brackets 5 and the latter by the bearing brackets 6b. An apron 10 which may be made from cloth, rubber, leather or any other suitable material, overlies the 80 base 1, and is provided at its ends with loops 11 through the medium of which it is connected to the pins 8 and 9. The apron 10 lies in contact with the base 1, and a portion thereof is located 85 in the recess 3 to provide a loop 12 for the reception of the tobacco from which the cigarette is to be made.

A roller 13 mounted upon a carrier 14 is positioned between and extends transversely of the base 1 and apron 10. The carrier 14 comprises 90 slides 15 which are connected at their upper ends by a bar 16 and in the upper end portions of which the ends of the roller 13 are journaled. The slides 15 rest upon the base 1, and are provided at their lower ends with outwardly directed flanges 95 17 which engage in the guide grooves 7 to connect the carrier 14 to the base for longitudinal sliding movement with relation thereto and to the apron 10 which passes over the roller 13.

In practice, to adapt the machine for rolling a cigarette, the carrier 14 is moved on the base 1 into a position between the recess 3 and the flange 4. The roller 13 over which the apron 10 extends is now located to the left of the recess 3 and above the open upper side of the loop 12 formed by depressing a portion of the apron into the recess 3. The tobacco from which the cigarette is to be made is placed in the apron loop 12, as indicated at 18, and the paper 19 from which the wrapper of the cigarette is to be made is placed upon the 110

apron 10 to the right of the loop. The carrier 14 is now to the right on the base 1. During this actuation of the carrier 14, the roller 13 moves with relation to the apron 10. During its movement across the recess 3, the roller 13 closes the upper side of the tobacco carrying loop 12 of the apron 10. After it passes the recess 3, the roller 13 carries the closed tobacco carrying loop 12 out of the recess 3 and maintains the loop closed until it reaches the right hand end of the base 1. As different portions in the length of the apron 10 form the loop 12 during the movement of the roller 13, the tobacco will be rolled within the paper 19 as the roller progresses; and when the roller reaches the limit of its movement the loop will be opened and the roller cigarette discharged onto the offset base portion 6.

As the base 1 and its parts 2, 4, 5 and 6, together with those parts forming the guide grooves 7, are formed integrally, all of these parts may be stamped up from sheet metal. The carrier 14 may also be stamped up from sheet metal. In view thereof, as the apron 10 may be readily engaged with the pins 8 and 9 and the pins 25 readily engaged with the bearing brackets 5 and 6b, as the roller 13 may be readily mounted upon the carrier 14, and as the carrier may be readily engaged in its guide groove 7, the machine may be readily manufactured and assembled at low 30 cost. The base 1 may be held in one hand and the carrier 14 actuated with the other during the rolling of a cigarette. If desired the base may

be placed on a table or any other support during the rolling of a cigarette, and when this is done the offset portions 2 and 6 of the base will support the base from the table or the like so as to permit it to be conveniently gripped and held while actuating the carrier 14.

While I have described the principle of the invention, together with the structure which I now consider the preferred embodiment thereof, it is to be understood that the structure shown 85 is merely illustrative and that such changes may be made, when desired, as fall within the scope of the invention as claimed.

What is claimed is:—

A cigarette rolling machine comprising a plate, 90 a pocket formed transversely of the length of the plate and intermediate the ends thereof, the pocket also constituting means for supporting one end of the plate upwardly from a plane surface, brackets integral with the opposite end of the plate, said brackets constituting a second supporting means for holding the plate upwardly from and parallel with a plane surface, guide members formed with the sides of the plate, a U-shaped carriage having outturned end portions 100 slidable in said guide members, a roller journaled in the parallel legs of the carriage, an apron overlying the plate and pocket and engaging over the roller, and means for securing the ends of the apron against movement.
